UNITED STATES PATENT OFFICE.

OSCAR WOODWARD, OF BABYLON, NEW YORK, ASSIGNOR TO REMINGTON TYPE-WRITER COMPANY, OF ILION, NEW YORK, A CORPORATION OF NEW YORK.

TYPEWRITING-MACHINE.

1,391,155.

Specification of Letters Patent. Patented Sept. 20, 1921.

Application filed May 3, 1919. Serial No. 294,555.

To all whom it may concern:

Be it known that I, OSCAR WOODWARD, citizen of the United States, and resident of Babylon, in the county of Suffolk and State 5 of New York, have invented certain new and useful Improvements in Typewriting-Machines, of which the following is a specification.

My invention relates to tabulator mechanisms for typewriting and like machines.

The main objects of my invention, generally stated, are to provide comparatively simple means by which the tabulator mechanism may be easily assembled and adjusted, 15 and by which parts thereof, together with their actuating links, may be readily detached and removed as a unit when desired.

Heretofore in tabulator mechanisms it has been common to provide flat spring clips 20 for detachably retaining connecting links in pivotal connection with associated parts, and to detach one end of each of said links, allowing the links to remain in the machine while parts of the tabulator previously connected thereto were detached from the machine. In connecting and disconnecting such links it has been customary to employ 25 a screw driver, or some such tool, to bend each retaining spring clip to one side and hold it in such position during the connection or disconnection of the associated link with its companion part. This required considerable time both in assembling and disassembling, as well as in adjusting the 30 parts; and the exercise of great care was necessary to avoid damaging the spring clips, which in being flexed to releasing positions were often broken, or so bent as to remain permanently set and hence rendered 35 useless or ineffective. Moreover, the connecting links dangled from the machine when the tabulator frame was removed, and in handling the machine such links often became accidentally bent or broken and replacement was necessary, thus resulting in 40 the loss of parts and in further loss of time.

The objects of my invention, generally stated, are to provide a construction which overcomes these difficulties and objections, 45 avoids entirely the use of retaining spring clips and enables the connecting links to be removed as a unit with the tabulator frame, so that subsequent handling of the machine cannot result in damaging the connecting 50 links, and also enables an individual detach-

ment and reconnection of each link to be effected while the parts remain in the machine.

To the above and other ends which will hereinafter appear my invention consists in 60 the features of construction, arrangements of parts and combinations of devices, set forth in the following description and particularly pointed out in the appended claims.

In the drawing,

Figure 1 is a full-sized fragmentary vertical fore and aft sectional view of a No. 10 Remington machine with my invention embodied therein.

Fig. 2 is a fragmentary rear elevation of 70 some of the parts represented in Fig. 1.

Fig. 3 is an enlarged, detail, fragmentary, perspective view of the coacting ends of the detachable connection.

Fig. 4 is a detail plan view partly in section of one of the links and the parts to which it is connected.

My invention may be regarded as an improvement on the construction disclosed in my Patent No. 927,626, dated July 13, 1909, 80 and on the constructions disclosed in the patents to George A. Seib, Nos. 1,132,286 and 1,273,545, dated respectively March 16, 1915, and July 23, 1918. As shown herein my invention is embodied in a column selecting 85 tabulator of the same general character as disclosed in said patents to George A. Seib.

The frame of the machine comprises a base 1, corner posts 2 and a top plate 3. The tabulator frame is designated as a whole by 90 the reference numeral 4. This frame is detachably secured to the frame of the machine by any suitable means, such as by screws 5 which connect the lower end of the frame 4 to the base of the machine, and by screws 6 which connect the upper portion of said frame 4 to the top plate. A series of 95 tabulator stop actuating members or levers 7 are pivoted to the tabulator frame at 8, and are mounted and guided, and control the tabulator stops (not shown) in the usual or any desired manner. In the present instance it may be assumed that the tabulator stops are like those disclosed in the above mentioned Seib Patent 1,132,286 and are 100 controlled by the levers 7 in a like manner. A coiled expansion spring 9 is seated at one end against a shoulder 10 in the tabulator frame and bears at its opposite end against 105 a shoulder 11 formed on the associated lever 110

7, it being understood that one of these springs is provided for each lever 7. A forwardly extending arm 12 on each member 7 is connected in any suitable manner, preferably by being pivoted permanently at 13 to a connecting link, designated as a whole by the reference numeral 14. I prefer to make this a two-part extensible link comprising a rod 15 and a socket 16. Part 15 is threaded at one end at 15^a, to enter a threaded hole in the socket 16, which socket is pivoted at 13 to its associated lever or member 7. The forward end portion of each link is flattened at 17 and formed with a slot 18 which extends longitudinally of the link and is open at the forward end thereof, thus forming a forked end. The slotted portion of each link is received in an open-ended slot 19 in an associated key controlled member 20. It will be seen that the plane of each part 17 is at right angles to the plane of its associated key controlled member 20, and that each link and its associated member are slotted at right angles to each other, so that each of the companion parts may be received in the slot of the other part and form an inter-locking connection. This connection prevents a lateral movement of either part relatively to the other and forms a support for the forward end of the link on its member 20. However, this interlocking connection may be broken or the parts detached one from the other by a mere rearward independent movement of the link; or otherwise stated by an independent movement of the link in the direction of its operating movement.

The members 20, as shown in the present instance, are pivoted on a rod 21 secured at its ends to the base of the machine, and each member 20 is in the nature of an angular lever controlled by a tabulator key 22 in the usual manner.

It will be understood that when connection is once effected between the forward end of each link or rod 15 and its associated member 20, such connection is maintained by the forward pressure on the link exerted by the companion spring 9, through the associated stop actuating member 7. Should it be desired, for any reason, to effect a disconnection between a given link and its companion member 20, this may be done by simply moving the lower end of the associated lever 7 rearwardly, as indicated in dotted lines in Fig. 1. This results in moving the link connected with said lever 7 lengthwise and rearwardly in the direction of its operating movement and independently of the companion member 20, and a disconnection of the forward end of the link is thus automatically effected. It will be understood that in connecting the links 14 to the members 20 the lower end of each lever 7 is moved rearwardly as explained above, and

when the open mouth of the slot 18 in a link is brought opposite to or in register with the slot 19 of the associated member 20, the mechanic frees the lever 7 and the reaction of its spring 9 causes the parts to be automatically connected.

It will be observed that the slot 18 in the link is shorter than the slot 19 in the lever 20 so that the flattened portion 17 of the link may rest on the bottom of the slot 19 or upon the hook-like part 23 of the lever 20, while the side walls of the slot 18 embrace the neck-like portion 24 resulting from the formation of the slot 19 in the lever. Thus the two slots formed at right angles to each other provide means for supporting one end of the link and also for preventing accidental side-wise disconnection of said link, while at the same time providing means for ready detachability of the two members by a longitudinal rearward movement of the link.

The tabulator frame may be detached (after removing or backing up the screws 5 and 6) by a rearward movement of said frame which carries with it all of the links 14 as a unit, and without any preliminary releasing of the forward ends of the links from the members 20. In this movement of the frame the forward ends of the links slide out of the slots 19. The links being thus removed with the tabulator there is no danger of their being bent or broken in the subsequent handling of the machine.

An adjustment in the length of each link 14 is effected, when its forward end is detached, by turning the part 15 to screw its threaded end in or out within the socket part 16. By this adjustment the proper extent of forward throw of each stop controlled by a member 7 may be determined. It will be seen that such an individual adjustment for each stop may be readily effected, if desired, even after the parts are assembled by momentarily disconnecting each link from its member 20. Therefore an individual detachment of each link 14 from, and a reconnection therewith, its associated lever 20 may be readily effected while the parts are in the machine, and without detaching, disconnecting or removing any other part of the machine.

While I have shown my invention embodied in a No. 10 Remington typewriting machine it will be understood that the invention is not limited to its use in such machine.

What I claim as new and desire to secure by Letters Patent, is:—

1. In tabulator mechanism for typewriting and like machines, the combination of a detachable tabulator frame, a tabulator stop actuating member carried by and detachable with said frame, a key-controlled member carried by the frame of the machine, a link connected to and supported at one end by

5 said stop actuating-member and removable therewith when the tabulator frame is detached and by a mere withdrawal of the tabulator frame, and means for detachably connecting said link to and supporting it by the key controlled member to enable the withdrawal of the link in the manner described, said detachable means comprising an open-ended slotted portion in one of the 10 parts and a portion on the other part which enters said slotted portion.

2. In tabulator mechanism for typewriting and like machines, the combination of a detachable tabulator frame, a tabulator stop actuating-member carried by and detachable with said frame, a key controlled member carried by the frame of the machine, a link including means by which the length of the link may be adjusted at will, said link being 15 pivoted to and supported at one end by the stop actuating member and removable therewith when the tabulator frame is detached, and means for detachably connecting the other end of said link to and supporting it 20 by said key controlled member, the character of the detachable connecting means being such as to enable a detachment of the link to be effected by a mere lengthwise movement of the link from its normal position independently of the key controlled member. 25

3. In a typewriting machine, the combination of a detachable tabulator frame, a series of tabulator stop actuating-members carried by and detachable with said tabulator frame, a series of extensible links each pivoted to and supported at one end by one of said actuating-members and removable therewith when the tabulator frame is removed, a returning spring operative on each 30

of said actuating members to return the 40 same and the parts connected therewith to normal position, and a series of key-controlled members carried by the frame of the machine and to each of which one of said links is connected by a detachable connection 45 that supports the other end of the link and permits a withdrawal of the links with the tabulator frame without effecting a preliminary detachment of the links, the power of the returning springs being exerted to maintain the detachable ends of the links connected to said key controlled members. 50

4. In a typewriting machine, the combination of a member, a returning spring acting on said member to return it and the parts 55 connected therewith to normal position, a second member for operating said first mentioned member, an intermediate connecting element between and supported at its ends by said members, and means for detachably connecting said element to one of said members, said detachable connecting means being formed by slotting at right angles to each other the adjacent portions of the two parts to be connected so that each part may 60 be received in the slot of the other part and thus form an interlocking detachable connection that may be broken by a mere independent movement of one of the parts against the power of said returning spring. 65

Signed at the borough of Manhattan, city of New York, in the county of New York and State of New York, this 1st day of May, A. D. 1919.

OSCAR WOODWARD.
